(57) **CLAIM**

The ornamental design for a label rail assembly, as shown and described.

DESCRIPTION

FIG. 1 is a perspective view of a label rail assembly, constructed according to the new design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The figures show a symbolic break. The break lines, as well as any portion of the article between the break lines, form no part of the claimed design.

1 Claim, 7 Drawing Sheets
